UNITED STATES PATENT OFFICE.

FRANK P. OUDERKIRK, OF IMPERIAL, NEBRASKA.

FUEL-TANK OUTLET.

1,385,390.

Specification of Letters Patent. Patented July 26, 1921.

Application filed May 8, 1920. Serial No. 379,678.

To all whom it may concern:

Be it known that I, FRANK P. OUDERKIRK, a citizen of the United States, residing at Imperial, in the county of Chase and State 5 of Nebraska, have invented certain new and useful Improvements in Fuel-Tank Outlets, of which the following is a specification, reference being had to the accompanying drawings.

10 This invention relates to certain improvements in fuel tank outlets and has relation more particularly to a device of this general character especially designed and adapted for use in connection with the carburetor of 15 an internal combustion engine, and it is an object of the invention to provide novel and improved means whereby the fuel below a predetermined level within the tank constitutes a reserve supply, and which reserve 20 supply may be drawn upon for use at will.

Another object of the invention is to provide a novel and improved outlet for a fuel tank embodying a valve comprising two relatively movable members, each of said 25 members being tubular with the bores thereof substantially in continuity, each of said members being provided with a port in connection with its bore, one of said members being provided with a second port adapted 30 to register with the port of the second member, the flap through the port of the second member being under control of the first member.

An additional object of the invention is 35 to provide a novel and improved outlet of this general character comprising two tubular members having their bores substantially in continuity, one of said members being rotatable relative to the other, each of said 40 members being provided with a port in communication with its bore, the rotatable member in one position serving to close the port in the second member and to open said port when in a second position, together with 45 means for imparting rotation to the rotary member, said means operating automatically to maintain said rotary member at substantially the limit of its movement in either direction.

50 It is also an object of the invention to provide a novel and improved outlet of this general character including two relatively movable tubular members each provided with a port, one of said members being movable to open or close the port of the second

member and wherein means are provided for limiting the relative movement of the members in one direction and positively assure the maintenance of the port in the second member positively closed.

60 The invention consists in the details of construction and in the combination and arrangement of the several parts of my improved fuel tank outlet whereby certain important advantages are attained and the device rendered simpler, less expensive and otherwise more convenient and advantageous for use, as will be hereinafter more fully set forth.

65 The novel features of my invention will 70 hereinafter be definitely claimed.

In order that my invention may be the better understood, I will now proceed to describe the same with reference to the accompanying drawings wherein:

75 Figure 1 is a fragmentary view, partly in section and partly in elevation illustrating an outlet constructed in accordance with the embodiment of my invention.

Fig. 2 is a view, in top plan and of a dia- 80 grammatical character illustrating the operating means for the outlet as herein embodied, a second position being indicated by dotted lines.

Fig. 3 is an enlarged transverse sectional 85 view taken through the lower portion of the outlet showing the port for the reserve supply closed, and

Fig. 4 is a view in plan of one of the supporting members for the outlet as herein set 90 forth.

95 As disclosed in the accompanying drawings, T denotes a fuel supply tank of a conventional type and which has extending inwardly thereof through its lower wall a relatively short outlet pipe or cylindrical casing 1. The pipe or casing 1 is threaded through the wall of the tank T, or more particularly the reinforcing member 2, defining opening 3 in the wall of the tank, through which said 100 casing the pipe 1 is disposed.

The outer or exterior end portion of the casing or pipe 1 is enlarged whereby a shoulder 4 is provided and which shoulder limits the extent of insertion of the casing 105 or pipe 1 within the tank T. The outer or exterior end portion of the casing or pipe 1 also has its bore enlarged as at 5, and with which enlarged portion is adapted to be coupled a sediment bulb, if preferred or a pipe 110

line leading directly from said casing or pipe 1 to the carburetor of the internal combustion engine.

The portion of the casing or pipe 1 inserted within the tank T is provided in a wall thereof with a port 6, said port being positioned immediately adjacent the lower portion of the wall of the tank T, as is clearly illustrated in Fig. 1 of the accompanying drawings.

7 denotes a tubular valve stem of such diameter to permit its insertion within the tank T from below and through the opening 3. The upper end portion of the stem 7 is provided with a reduced extension 8 which, when the stem 7 is applied, is adapted to extend exteriorly of the tank T through an opening 9 in the top wall of the tank T and in vertical alinement with the opening 3. The stem is inserted within the tank T before the casing or pipe 7 is applied. Before the stem 7, or more particularly the extension 8 is applied, the plate or washer 10 is inserted within the tank T through the opening 3, said plate or washer 10 being of such diameter as to readily permit its passage through said opening. After the plate or washer 10 has been applied within the tank T the extension 8 of the stem is inserted through the opening 3 and through the opening 11 of the plate or washer 10. The stem 7 is then forced upwardly through the tank T until the extension 8 is disposed exteriorly of the tank T through the opening 9. The plate or washer 10 will be carried upwardly by contact with an annular shoulder 12 surrounding the inner end of the extension 8.

After this assembly a second plate or washer 15 is disposed around the exterior portion of the extension 8. The washer or plate 8 is substantially the same configuration and dimensions as the washer or plate 10 and said plates or washers 10 and 15 when applied are in overlying relation. The bolts 16 or other fastening means are then operatively engaged with the end portions of the plates or washers 10 and 15 and disposed through the adjacent wall of the tank T. By this means an effective bearing for the upper portion of the stem 7 is provided. It is also preferred that the gaskets 17 be interposed within each of the washers 10 and 15 and the adjacent face of the tank T, and which washers for convenient assembly may be adhesively or otherwise secured to the washers or plates 10 and 15, although this arrangement is not imperative.

The lower portion 18 of the stem 7 is reduced and said reduced portion has threaded engagement within the casing or pipe 1 and when applied said reduced portion 18 is of such length to extend across the port 6 hereinbefore referred to. The extension 18 is also provided with a port 19 which upon

partial rotation in one direction of the stem 7 is adapted to register with the port 6 in the casing or pipe 1. The stem 7 at a predetermined distance above the extension 18 is provided with a port 20 through which the fuel within the tank flows into the stem 7 and out through the casing or pipe 1 until the level of said fuel falls before the port 20. By this means a reserve supply of fuel is provided and which reserve supply can be used at will by rotating the stem 7 to bring the port 19 in register with the port 6. This provision of the reserve supply is of particular advantage in such localities where filling stations or other sources of fuel supply, are relatively a great distance apart. When the level of the fuel within the tank T drops within the port 20, the sputtering of the engine will give notice to the driver of the motor driven vehicle that the supply of fuel is running low, whereupon the driver will adjust the stem 7 to bring the ports 6 and 19 into register, whereby the reserve supply of fuel may be used and which reserve supply is preferably in such quantity as to permit the car to be driven for a considerable distance so that under ordinary conditions sufficient opportunity will be given to reach the filling station or other source of fuel supply.

Fixed to the exterior end portion of the extension 8 is a crank or rock arm 21 and pivotally engaged with the outer end portion of such crank or rock arm 21 is an end portion of the operating arm or lever 22 terminating at its opposite end into an annular member or loop 23. The annular member or loop 23 provides means whereby the requisite pulling may be impressed upon the rod or arm 22 when required. The outer end portion of the rod or arm 22 is slidably disposed through an opening 24 provided in the member 25 positioned in desired location with respect to the tank T and which member 25 in the present embodiment of my invention constitutes the front panel of the seat structure such as comprised in the well known Ford car and wherein the fuel tank is housed within said seat structure.

Mounted upon the inner end portion of the rod or arm 22 and at a point in close proximity to the crank or rock arm 21 is a stop 26. Bearing against the stop 26 is an end portion of the expandable member 27 herein disclosed as a coil spring encircling the rod or arm 22. The opposite end portion of the member or spring 27 is in contact with a disk 28 or the like mounted on the rod or arm 22 and which is in contact with the inner face of the member 25. The expandable member or spring 27 operates to constantly urge the crank or rock arm 21 inwardly whereby the stem 7 is maintained in a position whereby the port 6 is either fully opened or closed without any intermediate

adjustment. In Figs. 1 and 2 the stem 7 and the crank or rock arm 21 are shown in such position whereby the port 6 is opened and this position is assured by the limit of 5 movement of the crank or arm 22 as determined by contact of the member or loop 23 with the member 25. To close the port 6 the driver or other occupant of the automobile pulls the rod or arm 22 outwardly com- 10 pressing member or spring 27 and the momentum of such movement will cause the arm or crank 21 to pass dead center so that upon release of the pull upon the rod or arm 22 the member or spring 27 will automatically swing the crank or rock arm 21 in 15 a position whereby the port 19 of the stem 7 is moved completely out of register with the port 6 whereby said port 6 is positively and completely closed. The limit of the rocking 20 or rotary movement of the stem 7 when returning to close the port 6 is effected by contact of the annular shoulder 28, defining the inner end of the reduced portion 18, with the inner or inserted end of the casing or pipe 25 1. This, in practice, is of decided importance.

From the foregoing description it is thought to be obvious that a fuel tank outlet constructed in accordance with my invention is particularly well adapted for use 30 by reason of the convenience and facility with which it may be assembled and operated, and it will also be obvious that my invention is susceptible of some change and 35 modification without departing from the principles and spirit thereof and for this reason I do not wish to be understood as limiting myself to the precise arrangement and formation of the several parts herein 40 shown in carrying out my invention in practice except as hereinafter claimed.

I claim:

1. In combination with a reservoir, a tubular casing extending therein, said casing being provided with a port within the reservoir, a rotatable tubular stem supported within the tank, the inserted end portion of the stem and the inserted end portion of the casing being in telescopic relation, said stem being provided with a port registering with the port of the casing upon rotation of the stem in one direction and means coacting with the stem to automatically maintain the stem in a position with the port either in or out of register with the port of the casing, said stem being provided with a second port at all times in communication with the reservoir, the telescoping portions of the stem and the casing being threaded one upon the other, said casing and stem being provided with coacting means for limiting the rotation of the stem when the first port of the stem is out of register with the port of the casing.

2. In combination with a fuel tank for internal combustion engines having an outlet; a rotary valve for controlling such outlet comprising an open ended casing member having a lateral port, a valve member mounted to turn in said casing projecting from the upper end of the casing, having its lower end opening to the open lower end of the casing in all positions of the valve and having also two lateral ports, one above the other, the lower port being adapted to be brought into and out of register with the port in the casing member upon the rotation of the valve and means for limiting the rotary movement of the valve.

In testimony whereof I hereunto affix my signature.

FRANK P. OUDERKIRK.
